UNITED STATES PATENT OFFICE.

LOUIS S. ROSS, OF NEWTONVILLE, MASSACHUSETTS.

TORPEDO.

1,059,766.

Specification of Letters Patent.

Patented Apr. 22, 1913.

Application filed January 12, 1912. Serial No. 670,739.

To all whom it may concern:

Be it known that I, Louis S. Ross, a citizen of the United States, and a resident of Newtonville, in the county of Middlesex and State of Massachusetts, have invented an improvement in Torpedoes, of which the following description, in connection with the accompanying drawings, is a specification, like characters on the drawings representing like parts.

This invention relates to torpedoes, and more particularly to that class thereof adapted to be secured upon a rail and to be exploded by the wheels of a train.

In order that the principle of the invention may be readily understood, I have disclosed a single embodiment thereof in the accompanying drawing, wherein—

Figure 1 is a plan view of the blank wherefrom the torpedo embodying my invention is preferably made; Fig. 2 is a plan view of the complete torpedo, the torpedo securing means being partially broken away; Fig. 3 is an underneath plan view thereof; Fig. 4 is an end elevation thereof; Fig. 5 is a longitudinal vertical central section thereof; Fig. 6 is a view partially in plan and partially in longitudinal transverse section of a slightly modified form of my invention; Fig. 7 is an end elevation thereof; Fig. 8 is a longitudinal central vertical section thereof; Figs. 9 and 10 are respectively an edge view and a side elevation of the piece constituting the end walls of the torpedo; Fig. 11 is a view partially in plan and partially in longitudinal transverse section of a still further form of the invention; Fig. 12 is an underneath plan thereof; Fig. 13 is an end elevation thereof; Fig. 14 is a longitudinal vertical central section thereof; and Fig. 15 is a view similar to Fig. 8 but representing the reverse position of the end walls of the torpedo.

An important object of my invention is to provide a railway torpedo of simple and cheap but effective construction which may be readily secured upon the rail and which shall be of "non-flying" construction, thus eliminating all danger.

In accordance with the preferred form of my invention, I form the torpedo casing of a single piece of material, such as hard fiber or tough paper.

In Fig. 1, I have shown the blank from which preferably the torpedo is formed.

Therein it is represented as composed of the outer bottom portion 1, the top portion 2, the inner bottom portion 3 and the end portions 4, 5. The shape of these portions of the single integral blank may be altered within the scope of my invention. Preferably, however, each of them is substantially rectangular, the top portion 2 being preferably of slightly greater width than the bottom portions 1 and 3 for the effective reception and securing in position of the end portions 4, 5, here shown as having flanges 6 notched at 7-7 to permit the conformation of the flanges to the top 2. Preferably the blank is transversely crimped along the lines 8-8 of its top, so as to provide the sloping sides 9-9, thus giving the completed torpedo a trapezoid form. If desired, however, the torpedo may be arc-shaped in end elevation. Preferably the outer bottom portion 1 is also crimped along the lines 10, 10 to provide therebetween a shallow groove for the reception of the securing strap 11, which may be of any suitable character, such, for example, as a lead or spring steel strip adapted to extend transversely of the rail and to have its ends engage beneath the upper flanges thereof. Herein I have represented the securing means 11 as extending in such a direction that the end walls 4, 5 are in substantial parallelism with the sides of the rail, but if desired the securing means may extend in a direction at right angles to that shown, in which case the end walls 4, 5 will extend transversely of the rail. Preferably the securing strip 11 is positioned between the inner and outer bottom portions 1, 2, as most clearly represented in Fig. 5. The explosive composition received within the casing is of any suitable character, such, for example, as chlorate of potash, sulfur and charcoal with or without a gritty composition to secure the effective ignition of the ingredients. The blank of the casing is folded into the form described, the detonating composition being placed therein at a suitable step in the folding of the blank, and thereupon the blank is secured in folded position by a suitable cement, glue or other adhesive, which is preferably applied to the adjacent faces of the inner and outer bottoms 1, 2 and the flanges of the end walls 4, 5. If desired, I may provide a coating of sand or similar material upon the outer face of the bottom 1 to assist in preventing dis-

placement of the torpedo from the rail, and preferably the entire torpedo is waterproofed, as by dipping the same when completed in paraffin or some other suitable substance.

5 In Figs. 6 to 10 inclusive, I have shown a slightly different form of my invention wherein the blank from which the torpedo casing is formed is devoid of end walls. 10 Preferably the blank is composed of the portions 1, 2, 3 represented in Fig. 1, and in addition I provide two separate end walls or pieces 12, 13, which are substantially the same in form as the walls 4, 5, excepting 15 that they are provided with a flange 13 wholly encircling them, such flange being slotted as indicated at 14 if desired and dependent upon the precise form of the torpedo. In this form of my invention the 20 securing band 14 of any suitable character is also positioned between the inner and outer bottom members 15, 16. The top portion 17 is preferably of the form heretofore described in connection with Figs. 1 to 5. 25 In assembling the torpedo constructed in accordance with this form of my invention, the two bottom portions 15, 16 are cemented or otherwise secured together, and then the separate end pieces 12, 12 are secured in 30 place, as by coating their flanges 13 with a suitable adhesive.

That form of my invention shown in Figs. 11 to 14 differs from that shown in Figs. 1 to 5 inclusive or that shown in Figs. 35 6 to 10 inclusive preferably only in that the securing band 18 extends outside of the portion 19 of the bottom through the greater portion of the length of the torpedo, and then passes through slits formed in the bottom portions and in the flanges 20 of the 40 end walls 21. In this manner, I not only more effectively secure the strip or band 19, but I more effectively secure the end walls 21 in position. Preferably, however, I also 45 employ some suitable adhesive to assist in securing the end walls 21 in position. As above indicated, that form of my invention shown in Figs. 11 to 14 may be employed either with separate end walls 12 or walls 4, 5 integral with the body of the blank.

50 That form of my invention shown in Fig. 15 differs from that form shown in Fig. 8 only in that the end walls 22 are reversed in position, the flanges 23 thereof extending inwardly instead of outwardly, as represented in Fig. 8.

It will be observed that in each of the forms of my invention herein shown, the end walls are of material preferably uniform with that constituting the body of the casing of the torpedo. In other words, I do not provide end plugs or stoppers of cementitious or other friable material, but instead provide thin end walls which when 60 65 the torpedo is exploded are simply blown as

units from the torpedo, or possibly somewhat ruptured. Owing to the fact that said end walls are composed of paper, hard fiber or the like, no injury can be inflicted by them, even though they are not disintegrated by the force of the explosion. By providing the end walls of suitable fibrous material in sheet form, I not only cheapen the torpedo, but provide a construction whereby the torpedo casing may be readily 70 75 assembled.

It will be understood that in each of the forms of my invention, the securing means may be of any suitable nature, and that it may extend either in the direction shown 80 or in a direction at right angles thereto, and that the form or shape of the torpedo may be varied within the scope of my invention.

It is evident that in certain forms of my 85 invention, the form of the blank may be changed or modified, so as to present a double top and a single bottom member, in which case the two members of the top will be adhesively secured together. It will be 90 observed that the blank is crimped along the lines of union of the top and bottom members, so that the blank may be readily rolled or folded into position. By crimping the top member of the blank, I provide 95 a torpedo having well defined sloping walls extending transversely of the rail and up which the wheel more effectively rides. While the two sloping portions of the top may be prolonged so as to meet at a sharp 100 angle, I preferably space them by a flat portion as illustrated, thus securing a more effective ignition of the composition. The crimping of the blank along the lines of union of the bottom and top also serves to 105 strengthen the torpedo at these points and to prevent premature rupture thereat as is likely to occur when the torpedo is of arc-shaped form in cross section. It is evident that the blank may be stamped into the 110 shape shown in Fig. 1 at one operation, thus cheapening the cost of the torpedo and that by providing the described sheet like end walls, I also very considerably enlarge the 115 capacity of the torpedo.

120 It is evident that the end walls if flanged need not in all cases be notched, but that they may be fashioned in any suitable manner. Preferably the said end walls are of the same material as the body, and in any event are of comparatively thin sheet like material.

The securing strips of suitable character may be fastened to the torpedo body in any suitable manner otherwise than as shown, as, for example, by positioning them transversely of the body upon the exterior of the bottom wall and then cementing thereagainst and onto the bottom wall an additional strip of paper, hard 125 fiber or the like.

fiber or other material, preferably similar to that of which the torpedo body is formed. Each end wall of the torpedo casing constitutes a rigid truss, so that the casing effectively resists the very considerable pressure to which the torpedo is necessarily subjected in storage or transportation. This truss like action of the ends is present to an even greater degree when the ends are secured by sealing. Furthermore each of the ends is preferably provided with a lip or flange 6 which thus provides a pressure resistant sealing lip. Moreover, the width of each lip is sufficient to prevent, when the lip is sealed 10 in position, the entrance of moisture into the casing. It will be observed that each end extends from the bottom member of the casing in a direction at right angles thereto and that when sealed to the top member of 20 the casing the ends are normal to both the top and bottom. Thus the truss like action is preserved. I have so proportioned the length of the torpedo casing to the width thereof that the truss like action of the 25 sealed ends is distributed and maintained throughout the area of the casing, so that the whole casing is substantially rigid and effectively resists the pressure to which they are necessarily subjected in transportation 30 or in storage. Preferably I secure this result by making the bottom member 3 of the casing in the form of a square. In other words, the length of the casing preferably does not exceed the width thereof, and thus 35 the truss like action of the ends is transmitted from the ends to the mid-length portions of the casing. The truss like action of the ends is of great importance.

The torpedo casing is filled with the detonating material in the following manner: 40 One of the ends 4 or 5 is sealed in position as described, and then the detonating material is packed into the casing through the opposite open end. To effectively pack a 45 torpedo in this manner, it is essential that the closed end be secured strongly enough to resist the packing pressure. After the detonating material has been packed into the torpedo, the opposite end is sealed to the top 50 and a rigid structure is secured. So rigid is the torpedo because of the employment of the truss ends that I am enabled to employ a detonating composition in a loose or powdered form instead of molding it, as has 55 heretofore been largely practised. This effects a saving in the manufacture of the torpedo. The powdered form of the detonating composition is, however, exceedingly sensitive to friction, and were not the sealed cas- 60 ing rigid throughout its entire extent, the pressure to which the torpedo casings are subjected when they are packed for storage or transportation would explode them or 65 render them gravely liable to such explo- sion.

I am the first so far as I am aware so to proportion the dimensions of a railway torpedo composed of a single piece that a rigid structure is secured through the action of truss like ends. It will furthermore be observed that each of the ends is unitary and uninterrupted, thus securing the maximum effect of the truss action of the ends. It will furthermore be observed that the sealing edge of each end is of relatively short extent in the preferred embodiment of the invention, namely, that wherein the edges are integral with the bottom, thus avoiding a joint at the bottom.

Owing to the rigid nature of the torpedo casings, it is not necessary to pack the loaded torpedoes with extreme care for storage or transportation, because they are not liable to explode except when subjected to that extreme pressure incident to their use as a railway signal.

The material employed is tough and stiff, being preferably hard fiber.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A one-piece railway or like torpedo of tough, stiff fibrous, "non-flying" material comprising a folded, sheet-like, unitary casing of non-molded form consisting of a bottom member and a top member and upright end walls constituting rigid transverse trusses extending at right angles from one of said members and engaging the inner face of and sealed to the other member, the length of the folded casing being so proportioned to the length of the truss ends that the truss support of the ends is distributed and maintained throughout the area of the casing, and the latter when sealed is substantially rigid and non-collapsible under pressure incident to packing and storage; a suitable detonating composition within said casing and torpedo positioning means.

2. A one-piece railway or like torpedo of tough, stiff fibrous, "non-flying" material comprising a folded, sheet-like, unitary casing of non-molded form consisting of a substantially square bottom member, an oblong top member and upright end walls constituting rigid, transverse trusses extending unitarily at right angles from one of said members and engaging the inner face of and sealed to the other member, the sealed casing being substantially square in longitudinal cross section, whereby the truss support of the ends is distributed and maintained throughout the area of the casing and whereby the latter when sealed is substantially rigid and non-collapsible under pres-

sure incident to package and storage; a suitable detonating composition within said casing and torpedo securing means.

3. A railway or like torpedo of tough, fibrous, stiff "non-flying" material comprising a folded, sheet-like casing of non-molded form consisting of a bottom member and a top member integral with each other, and upright end walls constituting transverse, rigid trusses extending at right angles from one of said members, each of said ends having a pressure resistant lip or flange to engage the inner face of and secured to the opposite member, said ends being of tough, fibrous, "non-flying" material, the length of the folded casing being so proportioned to the length of the truss ends that the truss support of the ends is distributed and maintained throughout the area of the casing, and the latter when secured is substantially rigid and non-collapsible under pressure incident to packing and storage; a suitable detonating composition within said casing and torpedo securing means.
4. A one-piece railway or like torpedo of tough, stiff fibrous, "non-flying" material comprising a folded, sheet-like, unitary casing of non-molded form consisting of a bottom member, a top member and upright end walls integrally extending from the bottom member at right angles thereto and having at their upper edges pressure resistant sealing lips to engage the inner face of

said top member; said ends constituting rigid transverse trusses and the length of 35 the folded casing being so proportioned to the length of the said truss ends that the truss support of said ends is distributed and maintained throughout the area of the casing, and the latter when secured is substantially rigid and non-collapsible under 40 pressure incident to packing and storage; a suitable detonating composition within said casing, and torpedo positioning means.

5. A one-piece railway or like torpedo of 45 tough, stiff fibrous, "non-flying" material comprising a folded, sheet-like unitary casing of non-molded form consisting of a bottom member and a top member and upright end walls constituting rigid transverse trusses 50 and extending unitarily from the bottom member at right angles thereto and engaging the inner face of and sealed at their upper edges to the top member, said end walls each being of unitary, uninterrupted 55 formation; a suitable detonating composition within said casing, and torpedo positioning means.

In testimony whereof, I have signed my name to this specification, in the presence 60 of two subscribing witnesses.
